UNITED STATES PATENT OFFICE

2,454,935

CONTINUOUS WIRE AND STRIP ELECTRO-
PROCESSING MACHINEConstantine G. Miller, Chicago, Ill., assignor to
The Meeker Company, Chicago, Ill., a corpora-
tion of Illinois

Application June 27, 1945, Serial No. 601,837

1 Claim. (Cl. 204—209)

1

This invention relates generally to apparatus and particularly to improved methods for electro-processing of metal. The more important aspect of the invention involves electro-chemically cleaning and electro-plating continuously moving articles and material such as wire. This application is a continuation in part of my co-pending application Serial No. 245,169, now Patent No. 2,431,065, filed December 12, 1938.

The apparatus and method of this invention are specifically adapted for electro-plating round or flat wire, strip steel, metal ribbons, cables, tubing and the like.

It is an object of this invention to provide an improved electro-plating method or process which will rapidly and completely clean wire or metal strip material and apply a uniform adherent metal coating thereto while the wire is moved through a suitable machine.

Another object of the invention is to provide an improved electro-processing method for treating multiple strands of wire or strips wherein electric current is conducted to the strands by means of contact finger members which are self-adjusting and self-protecting.

A further object is to provide an improved electro-processing technique or method in which the distance between the cathode wire or wires being treated and the anode or anodes is maintained substantially constant notwithstanding the wearing down or disintegration of the anode brought about by the electrolytic action. Another object is to provide an improved method for electro-processing wire, metal strip, metal ribbons or cables in which the electrical energy required to carry on the electrolytic action remains substantially the same throughout the entire operation.

A still further object is to provide apparatus of this nature and more particularly an improved method of operating such apparatus in which an electrical contact member is caused to insure electrical contact with the moving wire or strip being treated at all times regardless of the smoothness or imperfections of the surface of the strip.

The above objects are carried out in brief by providing apparatus which lends itself to the improved methods of electroprocessing and in which the cathode wire being treated is caused to be moved closer to the anodes as the latter wear down by the electrolytic action to thereby retain a given distance between the cathode or cathodes and anode or anodes and the same effective internal resistance of the electrolytic bath.

In order that the conductors which supply electric power to the cathode wire or wires will continue to make contact with these wires when the latter are shifted nearer the anode from time to time, a special frame is provided which insures firm contact between the conductor and the wire or wires and this frame is mounted on a main frame which supports the cathode wire or wires so that as the latter is moved toward the anode the power carrying conductor or conductors are moved in like manner.

The invention will be better understood when reference is made to the drawings in which:

Figure 1 represents a general view of the cooling, circulating, and filtering system for maintaining the electro-galvanizing solution in proper working condition;

Figure 2 is a vertical sectional view transverse of the galvanizing tank with certain parts broken away, showing the adjustable contact finger frames and the mechanism by which the cathode wire or wires in addition to these frames can be lowered in order to make up for the wear at the anodes;

Figure 3 is a vertical sectional view taken along line 3—3 in Figure 2, and showing the particular construction of the adjustable contact fingers;

Figure 4 is a detail view of the adjustable finger frame taken on the line 4—4 in Figure 2 and looking in the direction of the arrows;

Figure 5 is a detail view of the adjustable frame construction taken on the line 5—5 of Figure 2 and looking in the direction of the arrows;

Figure 6 is a detail vertical sectional view taken along line 6—6 in Figure 1, looking into the end of the galvanizing tank and showing the arrangement of the electrolyte return conduit means.

Referring to the drawings in detail, the numeral 1 designates the pay-off and take-in reels or swifts employed for feeding the wires 2 as work pieces through the apparatus. These wires are passed under the guide or ducking sheaves 3 through an electrolytic solution contained in an electro-galvanizing tank 4. The wires constitute the cathode and are to be electroplated. Thereafter, they are run out of the galvanizing tank under the right-hand set of sheaves 3 and subjected to a spray rinse (not shown).

The electro-galvanizing solution as used in the galvanizing tank 4 is constantly removed from the tank, cooled or otherwise treated to replenish the metal, and returned to the galvanizing tank, as illustrated in Figure 1. In this arrangement, the

circulating pumps 5 have their pressure pipes 6 positioned at the forward end of the electroplating tank so as to move the electrolyte through the tank and discharge it through the pipes 7 into the cooling tower 8. From the cooling tower, the electrolyte flows by gravity through the pipe or conduit 9 into the circulating tanks 10 which are interconnected by the pipes 11.

Provision is made for storing a certain amount of the electrolyte in one of the circulating tanks 12. Entrance and exit of electrolyte from the tanks is valve controlled through the pipes 13 and 14 so that the electrolyte may be permitted to flow directly into the circulating tanks and/or storage receptacle 12 as required. Conduit 14 provides a common exit from the tanks of the electrolyte through the pipe 15 which forms a return inlet means for admitting electrolyte to the electroplating tank 4. The inlet pipe 15 is positioned at the opposite end of the tank from which the electrolyte is withdrawn, as illustrated in Figure 1.

The outlet opening of the pipe 15 is flattened and bent outward, as at 16 (Figure 6), so as to distribute the electrolyte over the surface level of the solution. An over-flow pipe 16a communicates with the pipe 15 and the top of one of the intercommunicating circulating tanks 10 to prevent over-flowing of the circulating tanks should they become filled for any reason.

Filtering of the electrolyte is provided for by means of the pump 17 and filter press 18. The outlet side of the filter press pump 17 is connected by the pipe 19 to the filter press and filtered electrolyte returns to the other side of the tank through the conduit 20. It is apparent that the electrolyte in the galvanizing tank is kept flowing from one end of the tank to the other by means of the circulating system in a direction counter-current to the directional movement of the wires through the electro-galvanizing tank.

The latter may be constructed of wood or metal and when of metal is preferably rubber or lead lined. There is positioned within the tank a series of vertically arranged spaced dams 21. These dams are made of wood, phenolic condensation product or any other suitable material which is resistant to the action of the electrolyte employed. The latter is forced to flow over each successive dam which dams are placed at the point of engagement of the electrical contact fingers 22 with the wires and between the opposed ends of the anode electrodes 23. In this way the electrolyte is circulated above the bottom of the tank and is kept in constant movement over the electrodes and the wires.

The anodes 23 extend lengthwise over the tank and parallel to the wires passing therethrough and rest on electrical conducting members 24. The latter are in turn supported on a framework 25 which is spaced from the bottom of the tank and secured thereto in any suitable manner. The conducting members 24 constitute preferably copper bars which are lead coated to prevent being attacked by the electrolyte.

The members 24 extend transversely of the tank and are electrically connected to the bus bars (not shown) running along the side of the tank for supplying electric current to the anodes. The current density employed may be upwards of 300 amperes per square foot. It will be appreciated that the electrical current carrying parts will be insulated from the tank, when made of metal, and will be spaced from the opposite polarity electrode.

Referring to Figure 2, it will be observed that

the electrical contact finger members 22 are mounted on the shaft 26 of the carrier frame generally designated 27. This carrier comprises the contact finger shaft 26 and glass rod 28 which are positioned transverse of the tank and are retained in the flanged and supporting member 29. The glass rod 28 positions the wires 2 with respect to the fingers 22 so that proper contact can be made with the wires by the fingers.

10 The entire unit is vertically adjustable in the brackets 30 by means of the threaded rod members 31. The latter extend through apertures in the overhanging bracket portion 32, and are secured thereto by the nuts 33 threaded onto the ends of the rods as shown in Figure 2. By advancing or retracting the nuts 33, vertical adjustment of the shaft 26 and glass rod 28 is obtained. The brackets 30 are fastened to the angle irons 34, forming the ledge at the sides of the galvanizing tank by means of the bolts 35.

15 Guide members 36 are positioned on the angle iron supports 37 by the bolts 38. The guides are supported below the laterally extending flange 39 as shown in Figures 3 and 5. These guides are provided with a slot 40 for accommodating the vertical movement of the member 29 and integral flange portion 39, as shown in Figures 3 and 5. The angle iron supports 37 are suitably anchored to the inner walls of the galvanizing tank, as shown in Fig. 2. The metal parts are rubber covered or otherwise insulated against contact with the electrolyte. Screw locked members 41 are provided adjacent the ends of the glass rod 28.

20 The purpose of this adjustability of the contact finger frame 27 is to maintain a constant distance between the wire or wires being galvanized and the surface of the anode or anodes 23 which are positioned below the wire. As the anodes wear away, that is, decrease in thickness, this frame can be lowered so that the wire and contact finger can be correspondingly lowered. In this manner, a uniform distance can be maintained at all times between the wires and the anode. This saves power and keeps the resistance between the anode and cathode more uniform. In this connection, it will be appreciated that means may be provided for adjusting the positioning of the anode relative to the wire or wires to achieve the same effect. All that is necessary is to have the contact fingers, wires and anodes mutually adjustable so that their relative positions may be varied to provide a predetermined distance between the anodes and the wire. As a practical matter, it is better to move the contact fingers and wires rather than the anodes on account of the fact that the anodes are quite heavy and cumbersome and unyieldy structure might have to be employed in case the anodes were adjusted with respect to the contact fingers and workpiece wires.

25 When the machine is first started up or the anodes have been renewed, assuming that the anodes are about two inches thick, and the wire passes from one inch to 1 1/4 inches above the anodes, it has been observed that in a matter of only a few days the anodes dissolve from the top and thereby reduce their thickness. Therefore, more resistance is set up and higher voltage must be used to maintain the same current density for the same rate of deposit, which results in more power being consumed per unit of metal deposited. As an example, if the wire is an average of one inch away at the start and if the anodes wear down to half the thickness, then the wire will be 30 two inches away from the anodes, and it would

require more voltage to force the current through and greater expenditure of power to deposit the required quantity of metal. However, by the use of the adjustable cathode finger and frame, as each row of cathode fingers are adjusted separately, these can be lowered gradually from day to day and the voltage remains the same and therefore the expenditure of power remains constant regardless of the size or thickness of the anodes.

Another advantage of being able to move the cathode and anodes with respect to one another and particularly in lowering the cathode in direct relation to the wear-down or disintegration of the anode is that the electrolytic action can be carried to a point where the anodes reduce to a mere sliver before they must be removed, thereby saving the expense of recasting large quantities of suitable anodes. A still further advantage is that in removing anodes, the small anode stubs can be piled on top of one another or on top of the new anodes and as many sections of cathode figures can be adjusted as desired just so they will maintain an equal distance relation between the cathode and the pile of small stubs throughout the tank.

The adjustability of the cathode wire or wires with respect to the anode or anodes also offers considerable advantage from the standpoint of cost production per ton of wire to be galvanized because the power consumed is maintained strictly constant notwithstanding the continual wearing away of the anode. Thus, the mill knows exactly what the power consumption will be per ton of wire for a given weight coating after a first trial run because this consumption will not change from day to day or from week to week.

Electrical contact finger construction

The improved construction of the electrical contact fingers 22 is shown in Figure 3. This member comprises a weight pressed finger or stem 42. The contact member may be made of brass or copper alloy or other suitable electrical conducting material having the required strength and hardness. The finger member is rotatably mounted on the shaft 26 which is vertically adjustable in the frame 27. Integral with or attached to the contact finger 22 is an arm 43 carrying a slideable weight 44. This weight may be positioned on the arm by means of a set screw 45 as shown in Figure 3.

Positioned around the finger member 42 there is a loosely fitted porcelain insulator covering 46. The covering is provided with a slot 47 which receives a cotter pin 48 driven tightly through the contact finger 42. Inasmuch as the opening 47 is much larger than the shank of the cotter pin, the porcelain cover 46 is permitted to slide over the finger. At the lower end of the cover 46 there are overhanging ear portions 49 between which the wire or strip being processed or treated passes. An opening 50 in the bottom of the porcelain covering allows the end portion 51 of the contact finger member to protrude and contact the wire or strip 2. The end of the finger portion 51 may be grooved or shaped to fit the surface of the strip or wire being contacted.

The upper part of the finger 42 terminates in an enlarged portion 52 which is provided with a rectangularly shaped socket opening for receiving the member 53. The latter forms a bell crank with the member 43 and is adapted to rotate about the shaft 26. It will be understood that the finger 42 and the member 53 may be integral, if desired. The members 52 and 53 are

bolted or secured together by means of a bolt 54 to which is also secured the electrical terminal 55. A flexible electrical conductor 56 connects the terminal 55 with the other terminal 57 which is in turn secured to the bus bar 58. The electrical connections are made in this manner to the negative side of the electric current generator (not shown) so as to make the wire the cathode in the electro-plating solution. The lower end 10 of the finger or stem 42 is accurately grooved to snugly receive the wire cathode.

When the wire or strip 2 is not passing through the jaws of the insulated member 46, the latter drops down and protects the end of the contact finger portion 51 from acquiring a layer of deposited metal. This avoids interference with the electrode function of the contact finger when a wire or strip is passing through the electroplating solution. When the contact finger is in place and 15 is riding on the wire, the latter holds up the porcelain cover 46 and allows the brass or contact finger portion 51 to ride directly on the wire. In this position the tip of the contact finger may 20 become coated with metal which is being plated on the wire, but as the splices and imperfections 25 on the wire pass along, the porcelain cover is moved up and down knocking off the loose spongy metal and thus maintaining a clean electrical contact. There is thus provided a novel self-cleaning and self-protecting electrical contact 30 finger mechanism. It is apparent that the substantially stationary contact finger and reciprocably movable porcelain cover structure is more effective in its cleansing and protecting functions 35 than would be the case if the covering were maintained stationary and the contact finger were permitted to move. Moreover, by always insuring an absolute and firm contact between the finger 42 and the wire or strip 2 due to the urge 40 of the weighted member 44 sparking and other electrical complications are avoided at the contact between the finger and the wire workpiece. It is, therefore, advantageous to assign the self-cleaning and self-protecting functions to the covering and not to the contact finger because the 45 covering can be readily permitted to move over the contact finger without causing any disruption of contact between the finger and the wire.

It will be understood that the invention is not 50 limited to the exact details of construction and operation since obvious modifications may be made in the disclosed method of galvanizing or in the apparatus for carrying out that method without departing from the spirit and scope of 55 the description.

Having thus fully described my invention, what I claim as new and desire to secure by Letters Patent is:

Apparatus for electroplating simultaneously a 60 plurality of strips comprising a tank containing electrolyzing solution, a plurality of fixed soluble anodes in said solution, means for moving said strips through the solution, and means for maintaining a relatively constant distance between 65 said strips and anodes, said last mentioned means comprising a frame including an upper and a lower rod extending in parallel relationship across said tank, said lower rod comprising a supporting member located beneath the strips and adapted 70 to be located beneath the surface of the electrolyzing solution and supporting said strips in parallel relationship, said frame having means for adjusting said lower rod and the strips supported thereon toward said anodes as said anodes 75 become smaller, a plurality of conducting fingers

7
 swingably mounted on said upper rod and yieldably held in contact with the strips, and an insulating sleeve mounted on each of said fingers, said means for maintaining a relatively constant distance between said strips and anodes including brackets mounted on the tank sides, vertically mounted screws and nuts mounted on said frame, said screws extending through said brackets and supported thereon, a pair of arms forming parts of said frame and extending downwardly on opposite sides of the tank and connecting together in rigid relationship said upper and lower rods for adjustably maintaining the position of said frame, including said lower rod, and guides on the opposite vertical sides of said tank for guiding said pair of arms, said lower rod and said conducting fingers and for opposing the frictional drag of said strips on said fingers and lower rod, said arms serving to maintain the proper distance between the lower ends of said fingers and said 20 lower rod.

CONSTANTINE G. MILLER.
